UNITED STATES PATENT OFFICE.

JOSEPH TWINEM, OF NEW YORK, N. Y.

DESIGN FOR A DUSTING-CAP.

44,458.

Specification for Design.

Patented Aug. 5, 1913.

Application filed January 24, 1913. Serial No. 744,037. Term of patent 7 years.

To all whom it may concern:

Be it known that I, JOSEPH TWINEM, a subject of the King of Great Britain, and residing in the city of New York, borough of Brooklyn, in the county of Kings and State of New York, have invented a new, original, and ornamental Design for a Dusting-Cap, of which the following is a specification, reference being had to the accompanying drawings, forming part thereof.

Figure 1 is a front perspective view of a dusting cap showing my design; and Fig. 2 is a rear perspective view of the same.

I claim:

The ornamental design for a dusting cap as shown.

JOSEPH TWINEM.

Witnesses:

THEO. G. HOSTER,
PHILIP D. ROLLHAUS.
